UNITED STATES PATENT OFFICE.

WHITNEY R. SPIEGEL, OF INDIANAPOLIS, INDIANA.

DESIGN FOR A CHILD'S ROCKER.

Application filed March 31, 1924. Serial No. 9,119. Term of patent 3½ years.

To all whom it may concern:

Be it known that I, WHITNEY R. SPIEGEL, a citizen of the United States, residing at Indianapolis, in the county of Marion and State of Indiana, have invented a new, original, and ornamental Design for Child's Rocker, of which the following is a specification, reference being had to the accompanying drawing, forming part thereof.

The figure is a perspective view of a child's rocker, showing my new design.

I claim:

The ornamental design for a child's rocker as shown.

In witness whereof, I have hereunto set my hand at Indianapolis, Indiana, this 27th day of March, A. D. one thousand nine hundred and twenty four.

WHITNEY R. SPIEGEL.
